UNITED STATES PATENT OFFICE.

WILLIAM STOTT, OF ROCHDALE, ENGLAND.

STOP-MOTION FOR DOUBLING-FRAMES.

1,395,529.

Specification of Letters Patent.

Patented Nov. 1, 1921.

Application filed May 20, 1920. Serial No. 382,923.

(GRANTED UNDER THE PROVISIONS OF THE ACT OF MARCH 3, 1921, 41 STAT. L., 1313.)

To all whom it may concern:

Be it known that I, WILLIAM STOTT, a British subject, residing at Rochdale, county of Lancaster, England, have invented certain new and useful Improvements in Stop-Motions for Doubling-Frames, (for which I have filed application in England, May 12, 1919, Patent No. 134,174,) of which the following is a specification.

10 This invention relates to a stop motion for doubling frames of the kind in which in the case of ring frames each bobbin, and in the case of flier frames each flier spindle, is driven by a cone clutch by means of which 15 the rotation of the bobbin of the ring frame can be stopped, and the flier spindle of a flier frame can be stopped by disengaging the clutch and simultaneously the top roller can be raised out of contact with the bottom 20 roller.

The invention is designed for application to rabbeth or self contained spindles and consists in the particular construction and disposition of parts whereby the rabbeth 25 driving spindle may be permitted to continue rotation, while in the case of a ring frame the bobbin is stopped, and in the case of a flier frame the flier carrying spindle is stopped, and the means by which the cone 30 clutch is separated and the top roller simultaneously raised out of contact with the bottom roller.

The invention will be fully described with reference to the accompanying drawing.

35 Figure 1 is a side elevation (partly in section) showing the invention applied to the spindle of a ring doubling frame.

Fig 2 is a plan of same.

Fig. 3 is a side elevation (partly in section) showing the invention applied to the 40 spindle of a flier frame.

Fig. 4 is a plan of the lifting lever G.

The rabbeth or self contained spindle A is formed with a cone a on its upper end and 45 is driven by a wherve a' and the bobbin B is carried by a member b with an internal cone at its lower end which rests upon the cone a forming therewith a friction clutch by which it is driven. The bobbin B rests upon 50 the flange b' of the member b and is caused to rotate therewith by pins b^2 projecting into holes or notches in the under side of the bobbin flange, or it may be otherwise connected therewith. The ring C is of ordinary construction mounted in a ring rail c ,

The bottom roller E is carried in brackets in the usual way. The top roller E' is carried in a U shaped bracket e , mounted on the end of a vertically sliding rod F, so that by raising the rod the top roller E' can be 60 raised out of contact with the bottom roller E. To the lower end of the vertically sliding rod a lifting plate G is fitted, being adjustably attached by a bracket f to be raised and lowered with it. The plate G is provided with an aperture to embrace the cone a , of the spindle A, and is fitted on its upper side with a friction pad g of leather or other suitable material. It is placed over the cone a and below the flange of the cone b so that 70 when raised it will lift the cone b out of contact with the cone a and at the same time stop the rotation of the cone b and the bobbin B, while the rabbeth spindle A continues to rotate.

In a convenient position on the rod F a bracket H is fitted to which a hand lever K is pivoted by which the rod F and with it the top roller E' and the cone and bobbin b and B are lifted when desired. The hand 80 lever K is pivoted on a stud h and is provided with a fulcrum k which rests upon an incline plane m on the supporting bracket M' affixed to the beam M of the frame. As the hand lever K is raised the fulcrum k 85 slides along the incline gradually forcing the rod F upward. A stop h' on the bracket H prevents the hand lever K falling below the horizontal. The hand lever K also serves as an anti-ballooning-plate between 90 the spindles.

Referring to Figs. 3 and 4, the rabbeth or self contained spindle is formed with a cone a^3 on its upper end, is driven by a wherve a^4 and a flier spindle A' carried by the rabbeth spindle, has attached to it at its lower end a hollow cone b^3 which engages with the cone a^3 and by which it is driven.

The bobbin B' is supported on a bobbin or builder rail in the ordinary way.

The rollers are similar to those shown in Figs. 1 and 2, and the top roller is supported from the vertical sliding rod F which is constructed and operated as described in those figures.

The lifting plate G' at the bottom of the vertically sliding rod F is of fork shape to embrace a neck on the cone b^3 below the flange a^2 , and is covered with a friction pad of leather g' affixed to it after it is placed 110

in position. The rotation of the flier spindle A' is stopped for piecing by the lever G' on the rod F raising the cone b³ from the cone a³, the rabbeth spindle A' continuing 5 to rotate.

The friction surface of the cone is increased by inserting studs of leather in the cones a and a³.

What I claim as my invention and desire 10 to protect by Letters Patent is:—

In a hand operated stop motion for the spindles of doubling frames, the combination with a rabbeth self contained spindle, a friction driving cone and a driven cone member thereon, of a vertically sliding rod placed 15 adjacent to the spindle, a bracket to support the rod and within which it slides, a bracket on the lower end of the rod, a friction brake plate affixed to the lower bracket to embrace

the driving cone on the spindle, and when 20 raised to engage the driven cone member, a bracket on the upper end of the sliding rod adapted to carry the top roller of the machine, a hand lever pivoted to the bracket on the sliding rod and a fulcrum on the handle 25 resting on the supporting bracket, all so disposed that on raising the handle the sliding rod is raised and with it the top roller and the driven cone member, and at the same time the rotation of the latter retarded and 30 stopped substantially as described.

In testimony whereof I have hereunto set my hand in presence of two subscribing witnesses.

WILLIAM STOTT.
